US00D974770S

(12) **United States Design Patent** (10) **Patent No.:** **US D974,770 S**
(45) **Date of Patent:** **** Jan. 10, 2023**

(54) **DISPENSING BRUSH**

(71) Applicant: **WHIRLPOOL CORPORATION**,
Benton Harbor, MI (US)

(72) Inventors: **Seth E. Bixby**, Stevensville, MI (US);
Marcus A. Cannon, St. Joseph, MI (US);
Sayer J. Murphy, St. Joseph, MI (US);
Jun Young Park, St. Joseph, MI (US);
Joel R. Shinaberry, St. Joseph, MI (US)

(73) Assignee: **WHIRLPOOL CORPORATION**,
Benton Harbor, MI (US)

(**) Term: **15 Years**

(21) Appl. No.: **29/796,212**

(22) Filed: **Jun. 23, 2021**

Related U.S. Application Data

(62) Division of application No. 29/762,539, filed on Dec. 17, 2020, now Pat. No. Des. 925,923, which is a division of application No. 29/660,260, filed on Aug. 20, 2018, now Pat. No. Des. 909,066.

(57) **CLAIM**

The ornamental design for a dispensing brush, as shown and described.

DESCRIPTION

FIG. 1 is a top perspective view of a dispensing brush according to the design;

FIG. 2 is a bottom perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The portions of the article shown in broken line form no part of the claimed design.

1 Claim, 8 Drawing Sheets
